(57) **CLAIM**

The ornamental design for an electrically assisted strider as shown and described.

DESCRIPTION

FIG. 1 is a perspective view of the electrically assisted strider showing our new design, with footpegs in a deployed position;

FIG. 2 is a front elevational view of the electrically assisted strider of FIG. 1, with the footpegs in an upwardly folded position;

FIG. 3 is a rear elevational view of the electrically assisted strider with footpegs in a deployed position according to FIG. 1;

FIG. 4 is a right side elevational view of the electrically assisted strider with footpegs in a deployed position according to FIG. 1;

FIG. 5 is a left side elevational view of the electrically assisted strider with footpegs in a deployed position according to FIG. 1;

FIG. 6 is a top plan view of the electrically assisted strider with footpegs in a deployed position according to FIG. 1; FIG. 7 is a bottom plan view of the electrically assisted strider with footpegs in a deployed position according to FIG. 1;

FIG. 8 is a right side elevational view of the electrically assisted strider with footpegs arranged in an upwardly folded position according to FIG. 2; and,

FIG. 9 is a perspective view of the electrically assisted strider of FIGS. 1-7 with footpegs in a deployed position according to FIG. 1, and with environmental structure.

The broken lines in FIGS. 1-8 depict portions of the electrically assisted strider that form no part of the claimed design, and the broken lines in FIG. 9 depict portions of the electrically assisted strider or environmental structure that form no part of the claimed design.

1 Claim, 9 Drawing Sheets
